Peter Scott

The subject referred to in these Letters Patent and making part of the same containing a description in the words of the said Peter Scott being of his improvement in the use and application of asbestos to protect fire proof Chests, boxes and closets from the action and influence of fire and explosive heat.

To all to whom these Presents shall come Be it known that Peter Scott of the City of Philadelphia in the County of Philadelphia and State of Pennsylvania have invented a new and usefull improvement in the use and application of asbestos to protect fire proof Chests, boxes and closets from the action and influence of fire and explosive heat and the following is a full and exact description of the construction and operation of said improvement. Asbestos has been heretofore used to guard against the action of fire, the more flexible qualities of it have been employed in the manufacture of combustible cloth. My improvement consists in the application and use of the same material in combination with substances and articles which have hitherto been exposed to the influence of fire without it but will now derive greatly increased security & protection from its use. These articles are fire proof chests, boxes, closets, doors, &c. in their different parts. The asbestos formed into sheeting, or in any other convenient form is used to cover the material of which the above mentioned or other similar articles are composed and thus employed it gives additional protection to these contents by preventing the wrapping or cracking of them. They are of themselves more or less liable when exposed to the influence of explosive heat. This use of asbestos has been an improvement of my own. Peter Scott of Philadelphia, No. 115 Market Street, D. Minot
